UNITED STATES PATENT OFFICE

ROBERT E. GALER, OF SEATTLE, WASHINGTON, ASSIGNOR, BY DIRECT AND MESNE ASSIGNMENTS, TO MINUTE ELECTRIC BROILER, OF SEATTLE, WASHINGTON, A CORPORATION OF WASHINGTON

ELECTRIC BROILER

Application filed January 22, 1929. Serial No. 334,198.

My invention relates to electric broilers, and consists of certain improvements which make them more convenient, compact, and efficient.

5 The object of my invention is to improve the device along the above lines. My invention consists of certain details of construction which are illustrated in the accompanying drawings, and which will be hereinafter described and finally defined in the claims which terminate this specification.

The accompanying drawings illustrate a broiler built in accordance with my invention.

15 Figure 1 is a front elevation of the broiler, the front heating plate being swung forwardly and down.

Figure 2 is a cross sectional elevation taken on a plane extending from front to rear, both 20 heating plates being up or in position of use.

Figure 3 is a top or plan view, a portion of the heating plates at one end being in section.

Figure 4 is a detail elevation, parts being 25 in section, of a tensioning means.

My invention concerns a broiler wherein two complementary racks are yieldingly supported in complementary frames, which frames are pivoted so that they may swing together,

30 or either one swing independently of the other upon the common axis, and in which the steak is broiled while held in a vertical position, and thrown down into a horizontal position to take it off, or one of the frames

35 held in such horizontal position to permit the steak to be laid thereon, whereupon the second frame and rack may be brought down upon the steak to clamp it and hold it, and the whole assembly then moved into vertical

40 position for broiling. Preferably there is associated with each frame a heating plate which swings with the frame and rack, but my invention is not restricted to this type alone, other than as defined by the claims,

45 and may be of the type in which a separate broiling chamber is employed, and the frames moved into this broiling chamber. Such a construction is shown in my Patent No.

1,746,698.

50 Each heating plate has a body 1 of refrac-

tory material which carries the heating elements, these, as illustrated, being coils 10 of resistance wire. The above elements would conveniently be mounted in a frame as of sheet metal 11, which protects the said elements and gives permanency thereto. Such frame is also conveniently provided with ears or arms 12 which contain pivot bearings engaging pivot pins 23, carried by the end walls 22 of the base or stand. Two such frames are 55 provided, both pivoting upon the same pivots 23 and swingable separately or together. A back 21, or stops carried thereby, limit upward swinging of the frames.

The enclosing metal casing preferably extends at the adjacent sides of the heating plates, so that when the two plates are swung together their edges meet, thereby tightly enclosing whatever is being broiled. The rear heating plate has a handle 13, which may be 60 fixed, and the front heating plate has a handle 14, this preferably being pivoted and having a latch member 15 on its inner end cooperating with a complementary catch 16 to hold the two plates together. A spring 17 65 normally holds them engaged, and permits release when desired. The two heating plates may thus be swung together or separately, as desired.

Each heating plate is provided with means 70 mounted or carried thereon for holding or clamping a steak or the like in place, in cooperation with like means carried by the complementary frame. Such a holder consists of a rack or frame 3, including parallel bars 75 30. This rack is yieldingly supported from the heating plate, as by links 31, so as to swing towards and from the central plane and maintain parallelism with the heating plate. An extension spring 35, anchored to 80 the frame 11 by one end, and passing over a segment 36 secured on the pivot center 37 of one of the links 31, tends to force the rack 3 inward, and a stop 38, engaging a shoulder 39 of the segment, serves to fix its 85 inward limit. It thus automatically adjusts itself to steaks of different thickness, and the racks may come closely enough together to 90 broil slices of bacon, or separate enough for a thick steak or chops. As additional sup- 95 100

ports for the lower edge of the steak, or whatever is in the broiler, the lowermost of the cross bars may project from the general plane of the rack, as indicated at 32, being 5 preferably on the front rack 3.

To secure equality of position of the two racks 3, I provide each, at respectively opposite ends, with a pin 33, and at the other end with a complementary slot 34. The slot 10 has sufficient length to insure entry of its pin. Being disposed one pin on each frame, when swung into vertical position the pin on each frame will engage the upper end of the slot in the other frame to prevent said frame 15 dropping without carrying the first frame. In consequence of this disposition of the pins and slots, the frames are maintained in symmetrical position relative to both heating elements, thereby insuring equal heating at each 20 side.

Springs 6 mounted on the pivot pins 23 are connected at one end to the end wall 22 of the base, or to a tensioning clip 60 pivoted on the pins 23 and held by a screw 61, 25 and at the other end the springs are secured to the frames 11, one spring to one frame and the other spring to the other frame. These are so as to assist in lifting their respective frames, and lose their tension as the lifting 30 progresses and the load becomes less. By their aid the combined frames may be supported in any intermediate angular position.

Leads 5 and 50 connect with the respective heating plates. A switch, the actuating lever 35 53 of which is engaged by a lever arm 43, is connected in these leads, and is supported in a switch box 52. The lever arm 43 has complementary arms 4 and 40 which are positioned to be engaged by an arm 41 carried 40 by one of the frames 11. This is shown as carried by the front frame 11, so that whenever the front frame has been moved sufficiently in a horizontal direction the composite lever 4-40-43 is moved to throw the 45 snap-over switch, represented by the arms 53, to cut out the current supply to the heating elements 10. Consequently, whenever the broiler is thrown into horizontal position to receive a steak or to permit a steak to be 50 taken therefrom, the current supply is cut off, and the danger of fire greatly lessened thereby.

It is essential to provide some means for collecting the grease which will drip from the 55 steak as it cooks. I have shown the lips 12, which form the lower portion of the frames 11 when in the upright position, inclined to direct the grease falling upon them inwardly toward the center of the frames, where it 60 may drip from the edges of these lips 12, and fall into a grease pan 25 supported in an aperture 24 in the shelf 20 in the base of the stand. This grease pan may be provided with handles 26, by which it may be with- 65 drawn for removal of the grease. To pre-

vent splashing of the grease as it drips from the lips 12 into the grease pan 26 the two ends and rear sides of the pan 25 are raised, as indicated at 27. The forward edge may not be raised, as now designed, since the 70 forward frame 11 throws down into position where it would interfere therewith, but there is little likelihood of grease spattering beyond the forward edge of the pan. The grease will drip through the lips 12, whether 75 the frames 11 be in the upright or in the horizontal position.

What I claim as my invention is:

1. A steak broiler comprising two opposed heating elements, each carrying its half of 80 steak supporting means, and a common pivot for both said heating elements, upon which they may be turned together or separately, and a base carrying said common pivot of said heating elements.

2. An electric broiler comprising two heating plates pivoted upon a common axis to swing separately or together, a holding rack for each heating plate, and links supportingly connecting each rack with its heating plate 90 to accommodate them at variable distances apart.

3. An electric broiler comprising two heating plates pivoted adjacent one edge, a holder for each heating plate comprising a rack having forwardly projecting mutually centering members at their lower edges, and links pivotally connecting said racks each with its respective heating plate, thereby to accommodate them to different distances of separation. 95

4. An electric broiler comprising two heating plates having pivot bearings adjacent one edge, a rack carried by each plate, a stand carrying pivots for said heating plates, and having a forwardly extending shelf and an upwardly extending back so positioned that the shelf will engage with the front heating plate when it is swung forward and down, and the back will engage the rear heating plate when it is swung upward, to thereby support said plates in respectively horizontal and in vertical positions. 100 105

5. In a broiler, two complementary frame members, means pivotally supporting said frame members to swing separately or together, angularly about said pivot support, and means carried by said frames for engaging food to be broiled. 115

6. In a broiler, two complementary frame members, means carried thereby for engaging and clamping food to be broiled, a pivot support for each of said frames at a common edge, means connecting said frames to swing on said support jointly between an upright 120 and a horizontal position, said latter means being releasable to permit independent swinging of either frame on such support. 125

7. In a broiler, two complementary frame members, means supporting said frame mem- 130

bers to swing jointly or independently angularly about a common pivot axis between a horizontal and upright position, said frames being separable by independent movement of
 5 one from a common position, electric heating elements carried by each frame, a rack carried by each frame and cooperating to support a steak, and means operable by movement of said frames into horizontal position to cut
 10 off the current supply to said heating elements, and operable by movement of the frames into upright position to cut in the current supply.

8. In a broiler, a frame, a rack and parallel
 15 swinging arms supporting the rack from the frame, a segment secured to turn with one of said arms, and an extension spring anchored at one end to the frame, and passing over and anchored to said segment, and a
 20 limit stop to position said rack normally in a selected position.

9. In a broiler, in combination, two complementary frame members adapted to receive and hold a steak therebetween, electric heating
 25 elements in said frames for broiling such a steak, a pivot support for each of said frames at a common edge, means connecting said frames to swing on said pivot support jointly between an upright and a horizontal
 30 position, said latter means being releasable to permit independent swinging of either frame on such support, a switch in the circuit including said heating elements, and means operable by that frame which is lowermost when in
 35 horizontal position to throw said switch off as this frame moves towards horizontal position.

10. The combination of claim 9, the switch-operating means comprising an arm secured
 40 to and projecting from the frame which is lowermost when both are in horizontal position, and the switch including a rocking lever having two fingers, one being positioned for engagement by said arm to throw the switch off as this frame moves towards horizontal position,
 45 and the other positioned for engagement by said arm to throw the switch on as this frame moves towards vertical position.

50 Signed at Seattle, Washington, this 15th day of January, 1929.

ROBERT E. GALER.
